UNITED STATES PATENT OFFICE.

KALLY M. DOKOFF, OF RED GRANITE, WISCONSIN.

SIFTER.

Application filed July 20, 1921. Serial No. 486,217.

To all whom it may concern:

Be it known that I, KALLY M. DOKOFF, a citizen of Bulgaria, residing at Red Granite, in the county of Waushara and State of Wisconsin, have invented certain new and useful Improvements in Sifters, of which the following is a specification.

This invention relates to sifting screens and has for its object the provision of a sifter of simple and compact form which may be easily operated and which will thoroughly agitate the material passing therover so that the valuable material will be readily separated from the particles of no substantial value. The invention seeks to provide a screen which will be so mounted that it may have a pivotal motion in transverse planes and will be provided with means whereby the material passing over the inclined surface of the plane will be deflected from side to side so that the entire volume of the material will be caused to roll or flow over the surface of the screen to effect the desired separation of the particles.

25 The invention is illustrated in the accompanying drawings and will be hereinafter fully set forth.

In the drawings—

Figure 1 is a perspective view of a sifter 30 embodying my invention;

Fig. 2 is a longitudinal section thereof;

Fig. 3 is a transverse section on the line 3—3 of Fig. 2.

In carrying out the invention, I employ a supporting frame 1 which may be of any substantial construction and is provided at one end with vertical extensions 2 connected at their upper ends by a cross bar 3, inclined braces 4 extending from the said cross 40 bar or the upper ends of the extensions to the side bars of the frame so as to provide a rigid structure. Wear plates 5 are secured upon the upper ends of the braces 4 for a purpose which will presently appear. Upon 45 the upper cross bar 3 and the cross bar 6, at the rear or lower end of the frame, I secure journal boxes 7 in which are journaled the pivot pins or studs 8 extending from the adjacent ends of the screen. The screen comprises imperforate side plates 9 and a perforated plate or screen proper 10 secured to

and extending between the lower edges of said side plates. The screen 10 terminates short of the upper or rear ends of the side plates and the said rear ends of the side plates are connected at their lower edges by an imperforate plate 11 upon which the material to be screened is deposited. By referring particularly to Fig. 2, it will be noted that this plate 11 is inclined relative to the perforated plate 10 so that the material deposited on said feed plate 11 will at once gravitate over the same onto the screen. At the center of the feed plate 11 on the upper side thereof is secured a V-shaped deflector 12 whereby the material deposited upon the feed plate will be directed toward the sides of the screen and will be thereby prevented from flowing onto the center thereof in a compact mass. Openings 13 are provided through the deflector and a portion of the finer particles of the material may pass through these openings onto the central portion of the screen so that the material will be effectually spread over the upper end of the screen. Inwardly projecting flanges 14 are provided along the lower edges of the side plates so as to reinforce the same and the side edges of the screen proper are secured to the under sides of these flanges by angle bars 15 which serve to reinforce the sides of the structure and firmly clamp the side edges of the screen plate in position and prevent buckling of the same. To the upper end of the feed plate 11 and across the under side thereof, I secure an angle bar 16 which reinforces said plate and prevents buckling thereof so that the said plate will be maintained in a proper flat condition to receive and deposit the material, a similar angle bar 17 being secured across the under side of the screen at the lower edge of the feed plate, as shown most clearly in Fig. 2, and the upper pivot 8 being secured to and carried by the said angle bar 17, as shown. To 85 the ends of the transverse angle bar 17, I secure bumpers 18 which are adapted to impinge upon the wear plates 5 as the screen is oscillated so as to limit the oscillatory movements and also jar the screen so that 90 the contents of the same will be shaken and the particles loosened so that the separation

of the valuable from the less valuable material may be more readily and efficiently accomplished. A similar angle bar 19 is secured across the lower end of the screen plate 6 and bumpers 20 are provided at the ends of this cross bar and adapted to impinge against stops 21 secured on the lower braces 22, extending between the side bars of the main frame and the supporting standards or legs 10 at the front end of the same. To maintain the front ends of the side plates 9 in the proper spaced relation and to reinforce the structure, an angle bar 23 is secured to the same and the ends of the said angle bar are 15 extended downwardly so as to be connected with the angle bar 19 and the bumpers 20. The lower pivot 8 is carried by the angle bar 23 and is provided with a stop flange 24 to abut the bearing 7 and prevent the 20 screen riding downwardly upon the main frame. The space below the angle bar 23 is open to permit discharge of the cleaned material and a chute or discharge spout 25 projects from the front lower end of the screen, 25 as shown. A longitudinal brace rod 26 is extended between and carried by the angle bars 17 and 19 centrally of the screen and bears against the under side of the screen plate 10 so as to prevent sagging of the 30 same, and on the upper side of the said screen plate, equi-distant from the sides thereof, I provide a supplemental screen plate 27 which is of a slightly arched form, as shown. Secured to the side plates 9 and the flanges 14, 35 at the lower edges thereof, are upper and lower deflectors 28 and 29 which project inwardly and downwardly from the side plates so that the material falling against the same in the operation of the screen will be turned 40 toward the center and prevented from accumulating at the sides of the apparatus.

Upon the supporting frame below the screen and transversely thereto, I journal a shaft 30 equipped with a band pulley 31 at 45 one end to which power may be applied from any convenient motor. At the inner sides of the frame, I secure upon the shaft 30 cams or tappets 33 which are disposed in the vertical planes of the sides of the screen proper 50 and have their high parts extended in diametrically opposite directions, buffers 34 being secured to the under side of the screen immediately over the said tappets or cams to receive the impact of the same. These 55 buffers may conveniently be resilient plates secured at their ends to the screen or the angle irons 15 and having their intermediate portions free and bowed, as clearly shown.

Means may be provided to take up slack 60 in the screen. I have illustrated a bolt 35 mounted in lugs on the under side of the screen and transversely thereof. By tightening these bolts slack will be overcome by causing the screen to buckle below the sup- 65 plemental screen 27.

The operation of the apparatus will, it is thought, be readily understood. The material to be screened is deposited upon the feed plate 11 and will pass downwardly over the same onto the screen plate 10, being 70 spread by the action of the deflector 12 in an obvious manner with some of the finer particles passing through the space between the upper end of the screen plate 10 and the upper end of the arched secondary screen 75 plate 27. The driving gear wheel 32 is then rotated and motion will be consequently imparted to the shaft 30 so that the tappets or cams 33 will strike against the bottom of the screen alternately and in rapid 80 succession thereby rocking the screen upon the pivots 8 so that the material will be thrown alternately from side to side as it flows down the inclined surface. The transverse vibration of the screen will obviously 85 prevent the material accumulating along the sides and the deflectors 28 and 29 will serve to deflect toward the center of the screen those portions of the material at the sides thereof which might otherwise tend to travel 90 in straight lines longitudinally of the screen. The material thrown toward the center of the screen will, of course, strike upon the upper convex surface of the secondary screen 27 and this impact will aid in agitating the 95 material so that the separation of the particles will be thoroughly accomplished. The less valuable or waste matters pass through the openings in the screen plates and may be permitted to accumulate upon the ground 100 below the screen, while the more valuable matter will pass over the chute or discharge spout 25 into any convenient receptacle placed below the same.

It will be readily noted that my screen is 105 very simple in the construction and arrangement of its parts and may be set up for use at a very low cost. A large quantity of material may be treated in a short period of time under very low power and a very 110 thorough agitation and separation of the various particles will be rapidly accomplished. While I have shown and described a single screen plate, it is obvious that the screens may be multiplied without any material change in construction, the height of the side plates being determined by the number of screens to be used.

Having thus described the invention, what is claimed as new is:

1. The combination of a supporting frame, an inclined screen disposed longitudinally of the same, bearings on the frame at the ends thereof, a pivot stud projecting longitudinally from the bottom of the screen near 125 the upper end thereof and fitted in a bearing at the upper end of the frame, a second pivot stud projecting from the upper edge of the screen at the lower end thereof and engaged in a bearing on the adjacent end of 130

the frame, and means below the screen acting on the bottom thereof to rock the screen about the pivot studs.

2. A transversely vibratory screen comprising a screen plate, imperforate side plates rising from the side edges of the screen plate, and a supplemental transversely arched screen plate disposed longitudinally

upon the first-mentioned screen plate at the center thereof and extending from end to end thereof with its edges spaced from the side plates.

In testimony whereof I affix my signature.

KALLY M. DOKOFF. [L. s.]
